US00D817208S

(12) **United States Design Patent** (10) Patent No.: **US D817,208 S**
(45) Date of Patent: ** May 8, 2018

(54) **DOORBELL**

(71) Applicant: **Amcrest Global Holdings Limited**,
Dublin (IE)

(72) Inventors: **Abdurahman Ravat**, Houston, TX
(US); **Tahir Ravat**, Dublin (IE); **Raheel
Nusratullah**, Houston, TX (US); **Wu
bin Liu**, Hengyang (CN); **Ti Liang
Hou**, Shenzhen (CN)

(73) Assignee: **Amcrest Global Holdings Limited**,
Dublin (IE)

(**) Term: **15 Years**

(21) Appl. No.: **29/607,293**

(22) Filed: **Jun. 12, 2017**

(51) LOC (11) Cl. **10-05**

(52) U.S. Cl.

USPC **D10/118.2**

(58) **Field of Classification Search**

USPC D10/104.1, 108, 116.1, 118, 118.2, 121,
D10/122-126; D16/202, 203, 208, 209,
D16/215; D13/171

CPC ... G08B 3/00; G08B 3/10; G08B 7/00; G08B
7/06

(57) **CLAIM**

The ornamental design for a doorbell, as shown and described, with no claim made to any particular color scheme.

DESCRIPTION

FIG. 1 is a front perspective view showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines are included for the purpose of illustrating portions of the doorbell and form no part of the claimed design.

1 Claim, 7 Drawing Sheets
